Chauncy D. Baker.

UNITED STATES PATENT OFFICE.

CHAUNCEY D. BAKER, OF CHICAGO, ILLINOIS.

COMMUTATOR OR ELECTRIC CIRCUIT-BREAKER.

SPECIFICATION forming part of Letters Patent No. 375,328, dated December 27, 1887.

Application filed November 24, 1886. Serial No. 219,851. (No model.)

To all whom it may concern:

Be it known that I, CHAUNCEY D. BAKER, residing at Chicago, in the county of Cook and State of Illinois, and a citizen of the United States, have invented a new and useful Improvement in Commutators or Electrical Circuit-Breakers, of which the following is a full description, reference being had to the accompanying drawings, in which—

10. Figure 1 is a side elevation. Fig. 2 is a top view, the block A being in section.

The object of my invention is to provide a commutator or circuit-breaker which can be used for increasing or decreasing resistance in an electrical circuit, and which can also be used as a switch to open or close one or more of a number of circuits, which I accomplish by means of a series of contact-wires or pieces of metal of different lengths, so arranged that 20 one or other desired number can be made to come in contact at one end with a movable metallic contact-piece, as illustrated in the drawings, and hereinafter described.

In the drawings, A represents a block of 25 wood or other suitable material which supports the commutator.

a b are two disks.

c are rods or bars located between and secured at their ends to the disks a b.

30. d is a pin secured to the block A.

e is a short cylinder placed centrally between and secured to the disks a b.

f is a roller pivoted between and to disks a b, so that it rotates with very little friction.

35. B is a bracket or support secured to the block A.

C is a bar or rod, one end of which is secured to the bracket B, and the other end is curved over between the disks a b.

40. g represents a number of small contact-wires secured to the bracket B. The free ends of these wires are bent over between the disks a b, as shown in Fig. 1. These wires are not of uniform length, but the end of each successive

45. wire is shorter than the preceding one, as shown in Fig. 2. The bar C and wires g are bent at their free ends, so that they can be brought into contact with the roller f by rotating the disks a b. The other end of each of these wires,

or wires connected therewith, is to be carried 50 to one end of a resistance-box, or to one of a number of incandescent lamps in circuit, there being in effect as many circuits as there are contact-wires. The wires from the other end of the resistance-box, or from the lamps, are to 55 be connected with the main circuit, as usual.

D is a binding-post, from which the wire h is carried to the bar or rod C. The remainder of the circuit is not shown, but may be completed in the usual manner.

60. The operation is as follows: As shown in the drawings, the disks a b are to be rotated by hand whenever desired, bringing the roller f in contact with the end of the bar C and with the free ends of one or more of the wires g, thereby completing the circuit from the binding-post D to the resistance-box or to one or more of the lamps in circuit. The resistance can be varied at pleasure by changing the position of the roller f and causing it to be in 70 contact with a greater or less number of contact-wires g.

Instead of completing the circuit by means of the wire h and bar C, the wire indicated by dotted lines in Fig. 2 might be carried from 75 the binding-post D to the metallic pin or stud d, in which case the circuit would be completed through the metal frame a b and roller f, instead of through the bar C and roller.

What I claim as new, and desire to secure by 80 Letters Patent, is—

A commutator consisting of wires of different lengths, each adapted to be connected at one end with a resistance-box or with an electric circuit, and a bar or rod, C, in combination with a rotating frame supported at its center on a pivot carrying a rotating contact-piece, f, adapted to be brought by the movement of such frame into contact with the free end of the wire or rod C and with the free 85 ends of one or more of such wires of different lengths, substantially as and for the purpose specified.

CHAUNCEY D. BAKER.
